UNITED STATES PATENT OFFICE

CHARLES RAY LOVEJOY, OF JAMESTOWN, NEW YORK

DESIGN FOR A STOVE PEDESTAL

Application filed June 8, 1932. Serial No. 44,018. Term of patent 14 years.

To all whom it may concern:

Be it known that I, CHARLES RAY LOVEJOY, a citizen of the United States, residing at Jamestown, in the county of Chautauqua and State of New York, have invented a new, original, and ornamental Design for Stove Pedestals, of which the following is a specification, reference being had to the accompanying drawing, forming part thereof.

Figure 1 is a front elevational view of a stove pedestal, showing my new design.

Figures 2 and 3 are perspective views of the stove pedestal shown in Figure 1.

I claim:

The ornamental design for a stove pedestal, as shown.

C. RAY LOVEJOY.
